UNITED STATES PATENT OFFICE

167,252

COMBINATION DENTAL AND MEDICAL EQUIPMENT STAND

Fay E. Bronk, Rochester, N. Y., and Walter D. Teague, Annandale, N. J., assignors to Ritter Company, Inc., Rochester, N. Y., a corporation of Delaware

Application September 22, 1951, Serial No. 16,719

Term of patent 14 years

(Cl. D24—1)

To all whom it may concern:

Be it known that we, Fay E. Bronk and Walter D. Teague, both citizens of the United States, residing at Rochester, in the county of Monroe and State of New York, and Annandale, in the county of Hunterdon and State of New Jersey, respectively, have jointly invented a new, original, and ornamental Design for Combination Dental and Medical Equipment Stand, of which the following is the specification, reference being had to the accompanying drawings, forming a part thereof.

Fig. 1 is a front perspective view of a combination dental and medical equipment stand, showing our new design with the instrument holder in closed position;

Fig. 2 is a similar view of the same as seen from the right in Fig. 1;

Fig. 3 is a view similar to Fig. 1 but showing the instrument holder in open position, and

Fig. 4 is a similar view as seen from the left in Fig. 3.

We claim:

The ornamental design for a combination dental and medical equipment stand, substantially as shown.

FAY E. BRONK.
WALTER D. TEAGUE.
